UNITED STATES PATENT OFFICE.

JULIAN H. KENDIG, OF PITTSBURGH, PENNSYLVANIA, ASSIGNOR TO TARENTUM BOTTLE MACHINE COMPANY, OF TARENTUM, PENNSYLVANIA, A CORPORATION OF PENNSYLVANIA.

BOTTLE-MAKING MACHINE.

1,132,855.

Specification of Letters Patent. Patented Mar. 23, 1915.

Application filed August 16, 1913. Serial No. 785,096.

To all whom it may concern:

Be it known that I, JULIAN H. KENDIG, a citizen of the United States, residing at Pittsburgh, county of Allegheny, and State 5 of Pennsylvania, have invented certain new and useful Improvements in Bottle-Making Machines, of which the following is a specification.

This invention has reference to machines 10 for making glass bottles and the like and it has for its primary object the provision of an improved machine of the semi-automatic type together with an improved arrangement of operating means therefor 15 whereby the machine is more effective and consistent in its operation. My invention also contemplates the provision in a fluid actuated semi-automatic bottle making machine, of an improved arrangement of valvular devices for controlling the various operative movements of the parts and the provision of improved means for actuating the valves. The foregoing, together with such 20 other objects as may hereinafter appear or 25 are incident to my invention, I attain by means of a construction which I have illustrated in preferred form in the accompanying drawings, wherein—

Figure 1 is a side elevation of a bottle making machine embodying my improved features; Fig. 2 is an end elevation of the machine shown in Fig. 1; Fig. 3 is a plan view of Fig. 1; Figs. 4 and 5 are diagrammatic illustrations of different operative positions 30 of the valve and operating mechanism.

Referring to the drawings, it will be seen that I have illustrated only the blank forming table of a bottle making machine with my improvements applied thereto, 40 though of course it will be understood that my invention is applicable to other machines of similar type. The machine comprises the usual framework or platform 7 having a centrally located standard or column 8 on which is rotatably mounted a blank or mold table 9 carrying in the particular embodiment shown four blank molds 10 suitably spaced apart. Mounted above the table 9 in position to aline with the blank mold is a blank-forming plunger 11 carried by the piston 12 mounted in the cylinder 13 which is supported by the columns 14 and 15. Mounted on the column 15 is a cylinder 16 which operates the shears 17.

55 The table is given a rotary step-by-step

movement so as to bring a pair of molds, one in position beneath the blank-forming plunger 11, and the other beneath the shears 17. The mechanism for imparting this movement to the table will now be described. Suitably supported on a frame 18 adjacent the standard 8 is a horizontally disposed cylinder 19 in which is mounted a piston 20 to which is secured a counter slide rod 21 by means of the connecting plates 22. The piston rod 20 extends beyond either end of the cylinder 19, and the slide rod 21, which is of substantially equal length, is supported intermediate its ends by the guide plates 23 secured to the ends of the cylinder. Rotatably mounted on the standard 8 is a collar 24 held in position by the bearing shoulder 25 formed on the standard 8 and provided with a projecting arm 26. The arm 26 is connected to a plug 27 on the slide rod 21 by means of the link 28. The arm 26 is provided with a spring-actuated pawl 29 which ratchets over inclined face blocks 29' (Fig. 3) on the under side of the table. From the foregoing it 70 will be apparent that as the piston rod 20 and slide rod 21 are reciprocated, the collar 24 will be given a rotary movement back and forth, and that the table will be advanced or rotated a step during the forward movement, and will remain stationary during the rearward movement of the piston rod 20. The apparatus thus far described is of the usual character.

Referring now to the arrangement of 90 piping for supplying pressure to the cylinders 13, 16 and 19, and also to the valvular mechanism for controlling such flow, attention is directed to Figs. 1, 3, 4 and 5. The movement of the plunger piston 12 is 95 controlled by means of what shall be termed the plunger control valve 30, which valve is mounted on the bracket 31 carried on the framework 7. The valve 30 is of the slide valve type and is provided with a plug 32 100 and also with three port openings, 33, 34 and 35, the port 34 being intermediate the ports 33 and 35, and being an exhaust port. A pipe 36 connects one end of the plunger cylinder 13 to the port 33, and a pipe 37 105 connects the other end of the plunger cylinder to the port 35. From inspection of Fig. 4 it will be seen that in one position the port 33 is uncovered and the port 35 connected with the exhaust port 34, and that 110

in the other position, the port 35 will be uncovered and the port 33 connected with the exhaust port 34. Mounted in the plug 32 and projecting beyond either end of the casting of the valve 30 is a rod 38. The rod 38 carries a framework comprising two end rods 39 and a side rod 40 parallel to the rod 38. One rod 39 is located on each side of the valve 30. The purpose of this framework will be hereinafter set forth. Secured to the forward end of the rod 38 is a cross bar 41. At the rear end of the piston rod 20 is an abutment 42 which is adapted to take against the rods 39 and move the plug 32. On the rearward movement of the piston rod 20 the plug 32 is moved to the position indicated in Fig. 4; while on the forward movement of the piston rod 20, the plug 32 is moved forward, covering the port 33 and establishing communication between the port 33 and the exhaust port 34.

Located adjacent the plunger control valve 30 are two valves 43 and 44 which control the supply of pressure to the cylinder 19. The valves 43 and 44 are provided with the plugs 45 and 46 and exhaust ports 47 and 48 respectively. The valve 43 is provided with the port 49 connected to one end of the cylinder 19 by means of the pipe 50; and the valve 44 is provided with a port 51 connected to the other end of the cylinder 19 by the pipe 52. The plug 45 is provided with a cross passage or port 53 and the plug 46 with a similar port 54; and the plugs are also provided with grooves 55 and 56 respectively. Pressure is supplied to the valves 43 and 44 by means of the pipe 57 leading to the ports 58 formed in the casings of the valves. The casing of each valve is also provided with a port 59 which opens into the port 58 in each casing and into the cylinders at either end of the plugs 45 and 46. The plugs are prevented from coming flush with the forward ends of the valve casings by means of the nipples 60 formed on the plugs. The rear ends of the cylinders are provided with port openings connected by a pipe 61 which leads to an exhaust valve 62 operated by the handle 63. The plug 45 is provided with a stem 64 which projects through the rear end of the valve casing and the plug 46 is provided with a similar stem. A pipe 50' connects one end of the cylinder 16 with the pipe 50 and the pipe 52' connects the other end of the cylinder 16 to the pipe 52.

In the position indicated in Fig. 4, pressure is exhausting from the forward end of the cylinder 16 through the pipe 50', pipe 50, groove 55 and exhaust port 47 in the valve casing 43; and pressure is exhausting from the forward end of the cylinder 19 through the pipe 50, groove 55, and port 47. The plugs 45 and 46 are in balance inasmuch as the pressure flowing into the

valve from the pipe 57 and ports 58 flows to either end of the plugs through the ports 59. Assuming that the lever 63 is pressed downwardly and the valve 62 opened, the pressure at the rear end of the plugs 45 and 46 is exhausted through the pipe 61 to the atmosphere and the pressure at the forward end of the plugs causes them to move rearwardly to the position indicated in Fig. 5, at which time the passage 53 establishes communication between the port 58 in the valve casing 43 and the port 49, the pressure flowing from said port through the pipe 50 to the rear end of the cylinder and through the pipe 50' to the rear end of the cylinder 16, causing the piston 20 to be moved forwardly and the shears 17 to close. The port 58 in the valve casing 44 is closed and the groove 56 in the plug 46 establishes communication between the exhaust port 48 and the pipe 52, the pressure in the forward end of the cylinder 16 and in the forward end of the cylinder 19 exhausting through the pipes 52' and 52, groove 56, and exhaust port 48.

In the position illustrated in Fig. 5, the piston rod 20 has not reached its extreme forward position and is still moving forwardly. The abutment 42 has come into engagement with the forward rod 39 and as the forward movement of the piston rod 20 continues, the abutment will move the rod 38 forwardly and the cross piece 41 carried on the rod 38 will take against the stems 64 on the plugs 45 and 46, moving the said plugs to forward position as shown in Fig. 4. In this position, the passage 54 establishes communication between the port 58 of the valve 44 and the pipe 52, and pressures from the pipe 57 flows through pipe 52 to the forward end of the cylinder 19 and through pipe 52' to the forward end of the cylinder 16, thus causing the piston rod 20 to move to rear position and the shears to open. The plug 32 of the valve 30, however, will be shifted so as to uncover the port 35 and establish communication between the port 33 and the exhaust port 34. Pressure is supplied to the valve 30 by the pipe 55 and the pressure will flow through the port 35 and pipe 37 to the upper end of the cylinder 13, causing the plunger to move downwardly, the pressure in the lower end of the cylinder 13 exhausting through the pipe 36, port 33 and port 34. As the rearward movement of the rod 20 continues, the abutment 42 takes against the rear rod 39 and the rod 38 and plug 32 are shifted to the position shown in Fig. 1 and the plunger is elevated or retracted from the mold. The parts now remain in the position shown in Fig. 1 until the operator again opens the exhaust valve 62 which causes the plugs 45 and 46 to move rearwardly.

After the completion of the forward move-

ment of the piston rod 20, when the parts are in position for the plunger to come down and form a blank, at which time the rod 20 is being returned to rear position for 5 the advancement of the table to the next station, it is desirable to have the table locked. The locking means comprises the vertical rod 66 adapted to engage holes 67 in cams secured to the bottom face of 10 the table and normally held in upper or locking position by means of the spring 68; the arm 69 which is pivoted at one end to a standard 70 for rocking movement about a horizontal axis and to which the rod 66 is 15 pivoted; a cam lever 71 is pivotally mounted in a standard 72; and an abutment 73 formed on the rear plate 22 carried by the rods 20 and 21. When the rod 20 moves forwardly the cam lever is released and the 20 spring 68 moves the rod 66 upwardly to lock the table, and when the rod 20 returns to rear position, the abutment 73 engages the cam lever, forcing it downwardly. The end of the lever engages the arm 69 and de- 25 presses it which in turn moves the rod 66 downwardly to release the table. It is ad- 30 vantageous to have the table start quickly when it moves from station to station and slow up at the end of each arc movement. 35 To accomplish this, I provide a plurality of tapering cam pieces 74 on the bottom face of the table in position to be engaged by the rod 66. After the table has started and trav- 40 eled a short distance, the rod engages a cam piece and the movement of the table is re- 45 retarded inasmuch as the spring 68 presses the rod tightly against the cam piece, offer- 50 ing a frictional resistance to the turning of the table which increases toward the end of 55 the arc movement of the table.

Briefly stated, the operation is as follows. The gatherer gathers a quantity of glass on a pontil and places it in position over a mold and, while doing so, depresses 45 the handle 63; the plugs 45 and 46 shift, causing the rod 20 to move forwardly to 50 advance the table one station, and also causing the shears to close, cutting off the glass from the pontil; the abutment 42 shifts the 55 valve 30 when the rod 20 reaches forward position, and the plunger 11 comes down and forms the blank, the table in the mean- 60 time being locked by the rod 66; the shifting of the valve 30 also causes the cross 65 piece 41 to move the plugs 45 and 46 to initial position, which results in the open- 70 ing of the shears and the return of the rod 20 to rear position to get a new grip on the table, the plunger remaining in the mold 75 during this movement; the rod 20 when re- 80 turning to rear position shifts the valve 30 to initial position, causing the plunger 11 to be retracted and effecting the release of the table. The machine is now ready for an- 85 other operation.

The arrangement is simple and the valvu- 90 lar devices are automatically but positively actuated so that regularity and effectiveness in operation is obtained.

What I claim is:

1. In a bottle making machine, a rotary 70 mold table, a cylinder, a piston for impart- 75 ing a step-by-step movement to said table, a pressure-operated reciprocable member coöperating with the molds to form the ar- 80 ticle, a valvular device for controlling the movement of the reciprocable member, means whereby the piston shifts said valvu- 85 lar device, a second valvular device control- 90 ling the movement of the piston, and means whereby the first valvular device shifts the second valvular device when the former is shifted by the piston.

2. In a bottle making machine, a rotary 85 mold table, a main cylinder, a piston there- 90 in for imparting a step-by-step movement to the table, a pressure-operated recipro- 95 cable plunger coöperating with the molds to form the article, a plunger control valve for controlling the movement of the plunger, 100 said valve being shifted by the piston, a pis- 105 ton control valve for controlling the move- 110 ment of the piston, and means whereby the plunger control valve positively shifts the piston control valve when the former is shifted by the piston.

3. In a bottle making machine, a rotary 105 mold table, a main cylinder, a piston there- 110 in for imparting a step-by-step movement to the table, a pressure-operated recipro- 115 cable plunger coöperating with the molds to form the article, a plunger control valve for controlling the movement of the plunger, 120 said valve being shifted by the piston, a pis- 125 ton control valve for controlling the move- 130 ment of the piston, and a stem for the pis- 135 ton control valve, the plunger control valve having means for moving said stem to shift the piston control valve when the plunger control valve is shifted by the piston.

4. In a bottle making machine, a rotary 115 mold table, a main cylinder, a piston there- 120 in for imparting a step-by-step movement to the table, a pressure-operated recipro- 125 cable plunger coöperating with the molds to form the article, a plunger control valve for controlling the movement of the plunger, 130 a stem for said valve positively actuated by the piston to shift the valve, a pis- 135 ton control valve for controlling the move- 140 ment of the piston, and a stem for the pis- 145 ton control valve, said stem being moved to shift the piston control valve by the stem of the plunger control valve when the latter is shifted by the piston.

5. In a bottle making machine, a rotary 140 mold table, a main cylinder, a piston there- 145 in for imparting a step-by-step movement to the table, a pressure-operated recipro- 150 cable plunger coöperating with the molds to 155

from the article, a plunger control valve for controlling the movement of the plunger, a stem for said valve positively actuated by the piston to shift the valve at the extremes of forward and rearward movement of the piston, a piston control valve for controlling the movement of the piston, and a stem for the piston control valve, said stem being moved to shift the piston control valve by the plunger control valve stem when the latter is shifted on the forward movement of the piston.

6. In a bottle making machine, the combination of a rotary blank table, a pressure-actuated reciprocating member for imparting a step-by-step movement to the table, a pressure-actuated forming mechanism adapted to coöperate with the molds to form the article, a valvular device for controlling the movement of the forming mechanism, means whereby the reciprocating member after it has moved a predetermined

distance shifts said valve, and a valvular device controlling the movement of the reciprocating member, said last valvular device being shifted by the forming mechanism controlling valvular device when the latter is shifted by the reciprocating member. 25

7. In a bottle making machine, the combination of a rotary mold table, mechanism for imparting a step-by-step movement to the table, a plurality of inclined surfaces on the table, and a rod normally held in spring-held engagement with the surfaces and exerting a gradually increasing frictional pressure on said surfaces as it rides thereon. 30

In testimony whereof I have hereunto signed my name in the presence of the two subscribed witnesses.

JULIAN H. KENDIG.
